Emmeline Young

A black and white photograph of a vintage typewriter. A sheet of paper is inserted, featuring handwritten text and a rectangular metal stamp. The stamp contains the number '1' and the word 'Inventor'. Below the stamp, the word 'Inventor' is written in cursive. To the left of the stamp, the letter 'B' is written above the number '4'. Below the stamp, the name 'Harry W. Bolens' is written in cursive. To the left of the name, the word 'Son' is written in cursive. To the right of the name, the signature 'Oscar H. Young' is written in cursive. Below the signature, the word 'Attorneys' is written in cursive.

UNITED STATES PATENT OFFICE.

HARRY W. BOLENS, OF PORT WASHINGTON, WISCONSIN, ASSIGNOR TO GILSON
MANUFACTURING COMPANY, OF PORT WASHINGTON, WISCONSIN.

CHAIR-BASE HUB.

1,180,001.

Specification of Letters Patent. Patented Apr. 18, 1916.

Application filed May 13, 1915. Serial No. 27,831.

To all whom it may concern:

Be it known that I, HARRY W. BOLENS, a citizen of the United States, and resident of Port Washington, in the county of Ozaukee and State of Wisconsin, have invented certain new and useful Improvements in Chair-Base Hubs; and I do hereby declare that the following is a full, clear, and exact description thereof.

10 My invention refers to swivel seat chair supports and has for its object to provide a simple, durable and light weight pressed steel hub for the supporting base mechanism, the said hubs constituting the journal 15 for the usual seat-supporting spindle.

In the practical development of my novel hub I employ a cap or top plate and a bottom plate preferably composed of sheet metal, which plates are connected by a centrally disposed spindle barrel, and a series 20 of spaced vertically disposed channel socket strips, whereby the assemblage, when properly secured preferably by spot-welding and riveting, forms a rigid, compact, light and durable skeleton hub member that can be 25 manufactured at a considerable reduction in cost over hubs usually employed for the purpose mentioned, it being understood that a single set of dies are employed for the series 30 of channel-strips, whereby they are interchangeable and a corresponding simple die operation is employed for manufacturing the top and bottom plates in quantities.

With the above object in view the invention 35 consists in various details of construction and combination of mechanical elements as set forth hereinafter with reference to the accompanying drawings and subsequently claimed.

40 In the drawings Figure 1 represents a partly sectional elevation of a hub embodying the features of my invention, the section being indicated by line 1—1 of Fig. 2; Fig. 2, a plan view of the hub with parts broken 45 away and other parts in section to show details of construction; Fig. 3, a side elevation of the hub, and Fig. 4, a face view of a blank from which channel strips embodying the features of my present invention are formed.

50 Referring by characters to the drawings, 2 represents a top-plate preferably circular, the same being provided with a central barrel-receiving aperture and a circular depression 2' about said aperture to form a ball-

race. The top-plate is also provided with 55 apertures for attaching thereto a series of channel-strips A to be more fully herein-after described. Flushly fitted into the top-plate aperture is a spindle-barrel B, the same being secured preferably by spot-weld- 60 ing. The lower end of the barrel carries a bottom-plate 3 which is provided with a central aperture for the reception of the lower end of said barrel and this aperture, in order to effect a simple connection be- 65 tween the bottom-plate, is cut back at intervals to form ears 4 which are flush with the outer surface of the cylindrical barrel. Thus the bottom-plate can be adjusted upon the barrel and secured by spot-welding or 70 other means at any predetermined distance from the top-plate, which distance is determined by the length of the channel-strips. The bottom-plate is also apertured in a similar manner as that mentioned in con- 75 nection with the upper plate for permanently attaching the before mentioned channel strips. The channel strips A, as best shown in Fig. 4, are formed from an ini- 80 tially flat blank having a backbone portion 5 which is flanked by wing portions 5'. The upper end of the blank is extended from the backbone portion into a V-shaped centrally apertured head 6, while the lower end of 85 the backbone portion terminates with a cen- trally apertured foot 6' that is concaved at its end to conform to the circular surface of the barrel.

As best shown in Fig. 1, when the blanks are formed by a suitable die operation for 90 finishing, the cap 6 is folded downwardly and outwardly at a right angle to the backbone portion and the foot 6' is folded inwardly at a corresponding angle thereto. The wings 5' are then folded outwardly at 95 an angle flaring from the backbone corresponding to the angular surfaces 6'' of the head 6. Hence it will be seen that the head 6 forms a templet and support for the outwardly folded wing portions of the channel 100 iron. The heads of a series of these channel-irons, as shown in the drawings, are secured to the top-plate by rivets 7, it being understood that the heads abut the bottom surface of said top-plate. The feet of the 105 channel-irons which are bent inwardly, rest upon the inner surface of the bottom-plate 3 and are secured thereto by rivets which

pass through the foot apertures and the apertures provided for their reception in the said bottom-plate. Hence it will be seen that a very simple and durable skeleton hub 5 member is thus formed by a simple operation of assembling the channel members, top and bottom plates and barrel and thereafter performing the spot-welding operations, together with the riveting operations for 10 securing the parts together. It is manifest that the series of channel-strips are spaced apart and grouped about the barrel to form leg sockets α between their companion wing walls, which leg sockets are contracted 15 slightly at their mouths, as best shown in Fig. 2.

I claim:

1. A sheet metal hub of the character described comprising a tubular barrel, top and 20 bottom plates secured to the ends of the barrel, a series of channel strips spaced apart and grouped about the barrel to form leg sockets therebetween, each channel strip comprising a backbone having a head and 25 foot folded from its end edge respectively of the top and bottom plates, and means for securing the head and foot to their respective engaged plates.

2. A sheet metal hub of the character described comprising a tubular barrel, top and bottom plates secured to the ends of the barrel, a series of channel strips spaced apart and grouped about the barrel to form leg sockets therebetween, each channel strip 35 comprising a backbone portion having wing portions flared outwardly therefrom, a head folded outwardly from the upper edge of the backbone, and a foot folded inwardly from the lower edge of said backbone, and

means for securing the head and foot to the 40 top and bottom plates.

3. A sheet metal hub of the character described comprising a tubular barrel, top and bottom plates secured to the ends of the barrel, a series of channel strips spaced apart 45 and grouped about the barrel to form leg sockets therebetween, each channel strip comprising a flat backbone portion having side wings folded outwardly therefrom to form the opposite walls of said leg sockets, 50 a head folded outwardly and between the wings to form a closure at their upper ends, a foot constituting an extension of the backbone and folded inwardly, the head and foot being in abutting engagement with the top 55 and bottom plate respectively, and rivets for securing said head and foot to the aforesaid plates.

4. A sheet metal hub of the character described comprising a tubular barrel, top and 60 bottom plates secured to the ends of the barrel, a series of channel strips spaced apart and grouped about the barrel to form leg sockets therebetween, each channel-strip 65 comprising a flat backbone portion having outwardly divergent side wings, a V-shaped head folded outwardly adapted to fit between the upper edges of the flared side wings and form a flush joint therewith, a foot folded inwardly from the backbone 70 portion of the channel strip, and means for securing the head to the top-plate and foot to the bottom plate.

In testimony that I claim the foregoing I have hereunto set my hand at Milwaukee, 75 in the county of Milwaukee and State of Wisconsin.

HARRY W. BOLENS.
